UNITED STATES PATENT OFFICE.

RANSOM E. OLDS, OF DETROIT, MICHIGAN.

DESIGN FOR A VEHICLE-BODY.

SPECIFICATION forming part of Design No. 34,831, dated July 23, 1901.

Application filed June 5, 1901. Serial No. 63,312. Term of patent 14 years.

To all whom it may concern:

Be it known that I, RANSOM E. OLDS, a citizen of the United States, residing at Detroit, in the county of Wayne and State of Michigan, have invented and produced a certain new and original Design for a Vehicle-Body, of which the following is a specification, reference being had therein to the accompanying drawings, in which—

10 Figure 1 is a side elevation. Fig. 2 is a perspective view.

The sides of the body are parallel and of similar form. Each comprises an oblong rear portion A and a concavo-convex forwardly-projecting portion B, terminating in a scroll-like curve C, which rises to a slightly greater height than the rear portion of the body. The oblong portion is divided by a curved

one being of slightly greater width than the rear one. Centrally of the panel a is an oval ornament E.

The leading feature of the design is the configuration of the sides, having an oblong rear portion and a concavo-convex forward portion, the latter terminating in a scroll-like curve which rises to a slightly greater height than the rear portion of the body.

What I claim as my invention is—

The design for a vehicle-body, substantially as herein shown and described.

In testimony whereof I affix my signature in presence of two witnesses.

RANSOM E. OLDS.
